(57) **CLAIM**

The ornamental design for a model vehicle trailer light mount as shown and described.

DESCRIPTION

FIG. 1 is an upper, left, front perspective view of a model vehicle trailer light mount showing our new design; FIG. 2 is a lower, left, front perspective view thereof; FIG. 3 is a lower, right, rear perspective view thereof; FIG. 4 is an upper, right, rear perspective view thereof; FIG. 5 is a front elevation view thereof; FIG. 6 is a rear elevation view thereof; FIG. 7 is a right side elevation view thereof; FIG. 8 is a left side elevation view thereof; FIG. 9 is an upper plan view thereof; FIG. 10 is a lower plan view thereof; and, FIG. 11 is an upper, right, rear perspective environmental use view of the model vehicle trailer light mount.

In the drawings, the broken lines illustrate portions of the model vehicle trailer light mount that form no part of the claimed design; whereas, the additional broken lines in the environmental use drawing also form no part of the claimed design and are provided for the purposes of illustrating environmental use, structure, and context.
